CLAIM

The ornamental design for a two piece container, as shown and described.

DESCRIPTION

FIG. 1 is a front, side perspective view of a two piece container showing my new design;

FIG. 2 is side view of the two piece container of FIG. 1;

FIG. 3 is a rear side view of the two piece container of FIG. 1;

FIG. 4 is top view of the two piece container of FIG. 1;

FIG. 5 is a bottom view of the two piece container of FIG. 1;

FIG. 6 is a cross sectional view of the two piece container of FIG. 1; and,

FIG. 7 is a top perspective view of the two piece container of FIG. 1, inserted into another container.

The broken lines are for illustrative purposes only and form no part of the claimed design.
